UNITED STATES PATENT OFFICE

WALTER G. CRITCHLOW, OF WHEATON, ILLINOIS

DESIGN FOR A VAPOR HUMIDIFIER FOR INTERNAL COMBUSTION ENGINES

Application filed October 30, 1930. Serial No. 37,444. Term of patent 14 years.

To all whom it may concern:

Be it known that I, WALTER G. CRITCHLOW, a citizen of the United States, residing at Wheaton, in the county of Du Page and State of Illinois, have invented a new, original, and ornamental Design for a Vapor Humidifier for Internal Combustion Engines, of which the following is a specification, reference being had to the accompanying drawings, which form a part hereof.

My invention, as illustrated, relates to a vapor humidifier to be attached to the carburetor or to the intake manifold of an internal combustion engine.

In the drawings:

I claim:

The ornamental design for a vapor humidifier for internal combustion engines, as shown and described.

WALTER G. CRITCHLOW.
